US00D520981S

(12) United States Design Patent (10) Patent No.: US D520,981 S
Lee et al. (45) Date of Patent: * May 16, 2006

(54) PORTABLE TELEPHONE

(75) Inventors: Min-Hyouk Lee, Seoul (KR); Nam-Mi Kim, Seoul (KR); Chang-Hwan Hwang, Seoul (KR)

(73) Assignee: Samsung Electronics Co., Ltd., Kyunggi-do (KR)

() Term: 14 Years

(21) Appl. No.: 29/226,442

(22) Filed: Mar. 29, 2005

(51) LOC (8) Cl. 14-03

(52) U.S. Cl. D14/138

(58) Field of Classification Search D14/137, D14/138, 147-148, 247-248, 144, 341-347; 379/433.01-433.13, 434; D21/517; 455/575.3, 455/566, 575.1; 345/169; 348/376, 14.02

See application file for complete search history.

(57) CLAIM

The ornamental design for a portable telephone, as shown and described.

DESCRIPTION

FIG. 1. is a top front perspective view of a portable telephone showing our new design.

FIG. 2. is a front elevational view thereof.

FIG. 3. is a rear elevational view thereof.

FIG. 4. is a left side elevational view thereof.

FIG. 5. is a right side elevational view thereof.

FIG. 6. is a top plan view thereof; and,

FIG. 7. is a bottom plan view thereof.

1 Claim, 5 Drawing Sheets
